UNITED STATES PATENT OFFICE.

ADAM LIGHTELL, OF PORT ALLEN, LOUISIANA, ASSIGNOR OF ONE-HALF TO JAMES MURRAY, OF NEW ORLEANS, LOUISIANA.

TRACK-LAYING MACHINE.

1,215,172.

Specification of Letters Patent. Patented Feb. 6, 1917.

Application filed February 29, 1916. Serial No. 81,126.

To all whom it may concern:

Be it known that I, ADAM LIGHTELL, a citizen of the United States, residing at Port Allen, in the parish of West Baton Rouge and State of Louisiana, have invented certain new and useful Improvements in Track-Laying Machines, of which the following is a specification.

My invention relates to an improvement 10 in track laying machines, and appertains more particularly to that type of machine in which the rails and ties are joined together on a flat car behind the machine, from which they are removed and placed in position.

15 The object of my invention is to provide a derrick of novel construction which is capable of being fastened to the rail sections and kept parallel thereto until the track is laid. Other objects will become apparent 20 as the description proceeds and will be pointed out in the claims.

In the accompanying drawings,

Figure 1 is a side elevation showing a loaded flat car, and the loader or derrick car 25 at one end thereof at work;

Fig. 2 is a top plan view disclosing the mounting of the boom section on the frame of the machine;

Fig. 3 is a side elevation of the same;

30 Fig. 4 is a detailed perspective view of the grapping mechanism;

Fig. 5 and 6 are details of the grapping mechanism; and

35 Fig. 7 is a detailed perspective view of the vertical brace.

The frame 1 is mounted upon the wheels 2 and carries on the turn table 3 the floor 4. This floor 4 carries all the moving and rotating parts and is provided at the forward 40 end with a steel brace 5, which is maintained in a vertical plane by means of the braces 6 and 7. At each end of this brace 5 is provided a bearing which carries gear wheels 8 and 9. A hoisting drum 10 is supported on the floor behind the steel brace 5 over which a chain cable 11 passes. This chain 11 is adapted to run over the gear wheels 8 and 9 on the brace 5.

50 A derrick, or boom 12 is provided at its rear end with a bearing 13 in which is located the idler wheel 14, adapted to press against the brace 5, and is capable of move-

ment up and down thereon. This is rendered possible by fastening the chain 11 to some point on the rear end of the boom 12, 55 such as the bearing 13.

It will be seen that the rotation of the hoisting drum 10 controls the vertical movement of the rear end of the boom 12.

To the other end of the boom 12, as at 60 14', is fastened a cable 15, which passes over a pulley 16 on the mast 17 mounted on the floor 4, thence down to the hoisting drum 18. Both the drum 18 and the drum 10 are operated with power from the boiler house 19. 65

It will thus be seen that I have provided a device carrying a boom which is capable of being raised from either end, although, of course, it is obvious that it is intended to operate both ends together. In other words 70 the boom 12 is hoisted at both ends, then the turn table is operated until the boom is positioned above the flat car upon which the rails and ties are being made up, or upon which the completed sections are piled. 75 Then the boom is lowered into position, so that the grapping hooks may engage the rails of the section to be moved, then the boom is raised, the turn table rotates, and the section is placed on the ground, with 80 nothing remaining to be done but the joining of the ends of two sections together by fish plates.

And suitable means (not shown) may be provided for the movement of the car in 85 either direction.

In the construction of my invention I have found it expedient to use a grapping iron as shown, instead of the ordinary hook with which a derrick is provided. A rigid supporting bar 23 is provided with the two levers 25 and 26 pivoted at 27 and 28. At the bottom of the supporting bar 23 is pivoted, as at 29 and 30, the clamping bars 31 and 32. The lower end of each of these rods 31 and 32 is adapted to embrace one side of the steel rail upon the actuation of the levers 25 and 26, which are exerting a pull through the rod 33, whereby the rail is clamped between the rods 31 and 32. 95

At the bottom of the supporting bar is placed a cross strip 34 as a brace.

The levers 25 and 26 are provided with the ratchet members 25' and 26' adapted to 100

hold said levers where set. These grappling hooks are adapted to be supported from cross strips 35 on the boom 12.

I also provide any standard method of 5 turning the turn table on the support.

It is obvious that many slight changes could be made in this construction without departing from the spirit and scope of my invention, and I do not wish to be limited 10 to the precise structure set forth, but—

I claim:

1. In a track laying machine, the combination with a frame, of a turntable on said frame, a mast carried by said turntable, 15 bracing means independently mounted on said turntable, a boom mounted upon said bracing means, a cable connected between one end of the boom and the mast, means for operating said cable, a means for operating 20 the other end of said boom, said last mentioned means adapted to prevent oscillation of said boom.

2. In a track laying machine the combination with a rotatable frame, of a mast carrying a roller, a vertical brace, rollers mounted on said brace, a horizontal boom slidably mounted on said brace, a cable passing over said rollers on said brace and engaging said boom, means for operating said 25 cable, hoisting means connected to another portion of said boom and passing over the roller on said mast, means for operating 30 said hoisting means, and means for supporting a track to be laid:

3. In a track laying machine the combination with a rotatable frame carrying drums, of a mast mounted on said frame carrying a roller, a brace mounted independently of said mast on said frame, rollers on said brace, a boom carrying an 35 idler roller slidably mounted on said brace, hoisting means running from one of the 40

drums over the rollers of said brace engaging the boom, a second hoisting means fastened to the boom running over the roller 45 of said mast to another of said drums, and means on said boom for holding the rails.

4. In a track laying machine, the combination with a frame, of a mast mounted thereon, a vertical brace mounted on said 50 frame in a different location from but in a plane substantially parallel with said mast, a boom vertically movable upon said brace, means for raising and lowering said boom, and grappling means carried by said boom 55 for the engagement of track rails to be laid.

5. In a track laying machine, the combination with a frame, of a mast mounted thereon, a vertical brace mounted on said 60 frame in a different location from but in a plane substantially parallel with said mast, said brace comprising a plate having longitudinal ribs thereon, a boom vertically movable upon said brace, means for raising and lowering said boom, and grappling 65 means carried by said boom for the engagement of track rails to be laid.

6. In a track laying machine the combination with a frame, of a vertical brace mounted on said frame, sets of rollers mounted 70 in the extremities of said brace spaced apart, rotary means on said frame, a boom movably mounted against said brace, and sets of chains passing from one side of said 75 boom around the rollers, said rotary means and said other rollers, engaging the opposite side of said boom whereby vertical movement of the boom is provided for and oscillation of the boom is rendered impossible.

80 In testimony whereof I affix my signature:

ADAM LIGHTELL.
